UNITED STATES PATENT OFFICE.

WILLARD GEORGE STEADMAN, JR., OF SOUTHBURG, CONNECTICUT.

TOOTH-POWDER CONTAINER.

1,081,785.

Specification of Letters Patent Patented Dec. 16, 1913.

Application filed July 11, 1913. Serial No. 778,452.

To all whom it may concern:

Be it known that I, WILLARD G. STEADMAN, Jr., a citizen of the United States, and a resident of Southington, in the county of 5 Hartford and State of Connecticut, have made new and useful Improvements in Tooth-Powder Containers, of which the following is a specification.

My invention relates to improvements in 10 tooth powder containers, and it consists in the combinations, constructions, and arrangements herein described and claimed.

An object of my invention is to provide 15 a device for holding tooth powder with means for preventing the mouth of the container from engaging the wet brush, thereby obviating the danger of the powder becoming caked around the exit opening in a manner common with the ordinary container.

A further object of my invention is to 20 provide a device by means of which economy of the tooth powder is secured.

A further object of my invention is to 25 provide a container which will distribute the powder evenly on the brush.

Other objects and advantages will appear 30 in the following specification and the novel features of the device will be particularly pointed out in the appended claims.

My invention is illustrated in the accompanying drawings forming part of this application in which—

Figure 1 is a perspective view of the device, Fig. 2 is a section through the top portion of the device, Fig. 3 is a view showing the container inverted and the brush in position to receive the powder, Fig. 4 is a detail view of the top of the container, Fig. 5 is 40 a view similar to Fig. 4 showing a modified form, and Fig. 6 is a view showing a modified form of brush guard.

In carrying out my invention I provide a receptacle having a body portion 1 of any 45 suitable shape. Secured to the upper end of the body portion is a top 2 having a converging extended portion 3, which forms a delivery tube for the powder, this converging portion having either a continuous opening 50 such as that shown at 3^x in Fig. 4 or a series of perforations such as shown at 3^y in Fig. 5. The upper edge of the extension 3 is bent outwardly as shown in Fig. 2 and is arranged to receive a slideable cap 4 for covering the 55 delivery opening when the device is not in use.

On one side of the container is a guard 5. This consists preferably of a single piece of wire being bent to form a socket 5^x and having laterally bent end portions 5^y preferably of rectangular cross section arranged to enter underneath members 6, which constitute spring hinge members. These spring hinge members tend to hold the guard close to the surface of the container 65 in either the position shown in Fig. 1 or that shown in Fig. 3.

From the foregoing description of the various parts of the device the operation thereof may be readily understood. When 70 it is desired to use the powder the cap 4 is pulled outwardly so as to uncover the openings 3^x or 3^y, the guard is turned from the position shown in Fig. 1 to that shown in Fig. 3 and the brush is held underneath 75 the container. Now on moving the container the guard 5 will come in contact with the neck of the brush 7. This will serve the purpose of causing the powder to be shaken out of the container upon the brush and 80 will also prevent the brush from coming in contact with the mouth of the container thereby obviating the chance of the powder becoming wet and forming a cake at the mouth of the container. It will also be 85 noted that in both forms of the delivery tube the discharge is elongated and relatively narrow. When the guard is used the powder is deposited on the central line of the brush in a thin stream and there is 90 therefore little danger of the powder being wasted. Moreover the powder is evenly and uniformly distributed upon the brush. The cover 4 may be closed and the guard 5 swung back into its original position where 95 it is held by the spring hinges 6 close to the side of the container.

The container may be of any desirable material and the body of the container may be of any suitable shape such as round, oval, or square. The bottom of the container may be made detachable by means of spring clips, screw threads, or similar means, thus allowing the container to be refilled from powder in bulk.

I claim:

1. In a container for tooth powder, a body portion, a discharge tube secured to the top of said body portion and having an elongated discharge, a guard hinged to said body portion and arranged to be swung into operative position at one end of said dis-

charge, said guard being provided with a socket arranged to receive the neck of the tooth brush, and spring hinges for holding said guard in its operative and in its inoperative position.

2. In a container for tooth powder, a body portion, a discharge tube secured to the top of said body portion and having an elongated discharge, a guard hinged to said body portion near the top of the latter, spring hinges for holding said guard nor-

mally against the side of the container, said guard being arranged to be swung on its hinges so as to project above the discharge tube and being provided with a socket arranged to engage the neck of the tooth brush.

WILLARD GEORGE STEADMAN, JR.
